UNITED STATES PATENT OFFICE.

ANTON LINEE, OF CHICAGO, ILLINOIS.

WARDROBE BED.

SPECIFICATION forming part of Letters Patent No. 415,724, dated November 26, 1889.

Application filed October 22, 1888. Serial No. 288,874. (No model.)

To all whom it may concern:

Be it known that I, ANTON LINEE, a citizen of the United States, residing at Chicago, in the county of Cook and State of Illinois, have

5 invented certain new and useful Improvements in Wardrobe Beds; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

This invention relates particularly to folding wardrobe beds.

The object of the invention is to provide an easy-acting bed which shall be durable and attractive in form.

In the accompanying drawings, Figure 1 is 20 a side elevation, partially in section. Fig. 2 is a detail of one set of weights. Fig. 3 is a detail showing one of the hinge-bolts and corner-irons connected therewith. Fig. 4 is a perspective of the bearing for the hinge-bolt. 25 Fig. 5 is a front elevation of a portion of the bed. Fig. 6 is a horizontal section in line $\alpha\alpha$ of Fig. 1. Figs. 7 and 8 are detail views of the counterbalancing-weights.

A is the case.

30 B is the bed proper.

The case A is upright and open at the front, and has at its base the forward extension A'. The bed B is hinged by its head to the extension A' in such manner as to fold into or 35 against the case A, as is usual in this class of beds. The head of the bed is thus supported by said extension, and its outer end, when in the horizontal position, is supported by suitable feet, fixed or folding. A vertical

40 channel A² is cut into the inner face of each side wall of the extension A' from the top downwardly an inch or more, and the lower end of said channel is preferably protected by a metal bearing A³. Such bearing is shown 45 in perspective in Fig. 4.

A post B' projects outwardly from each side of the head of the bed into the adjacent channel A². Said post may have a head, and the channel may be enlarged within to make room 50 for said head, and said head may then rest behind said metal bearing to prevent the side

of the extension A' of the case A from being sprung outwardly away from the bed B. In the drawings said post B' is represented as a bolt.

B² is a corner-iron resting in the angle formed by the bottom of the bed and the side thereof. The arm of the corner-iron lying in contact with the bottom of the bed is secured to the latter by a screw or bolt b or 60 otherwise, while the bolt B' extends through the side of the bed and the arm of the corner-iron in contact therewith. At the outside of the side of the bed the bolt has a shoulder b² resting against said side. By drawing the 65 nut b³ the bolt, the side of the bed, and the corner-iron are bound firmly together, the head of the bolt projecting to enter the channel A². The corner-iron thus serves the double purpose of sustaining the bolt and the 70 side of the bed. A second corner-iron B³ may be placed over the outside of the corner of the bed opposite the corner-iron B², and pierced by the bolt B' and the bolt b, so that the one pair of bolts binds the two corner- 75 irons. This construction renders the corner very strong.

In the case A back of the space occupied by the bed B when folded are arranged vertically-sliding counterbalancing-weights C. 80 These run in any suitable guides C', and rest upon friction-rollers C², which rollers are supported by the head of the bed B. I prefer to arrange these weights in the corners of the case A in wells D, formed by the side and 85 back walls of the case A, and the walls D'D², any of said walls being provided with channel-guides C', into which tongues c³ project from the weight.

I prefer to make the weight of hollow wooden boxes filled with sand, gravel, or similar loose material, which may be supplied after the bed has been shipped and set up. This is a convenient and cheap method.

When the foot of the bed is lowered, the 95 head of the bed, together with the rollers C², is raised. By this means the weights C are raised. Said weights may be sufficient to fully counterbalance the bed or to more than counterbalance it, so that they will, if left 100 to themselves, raise the bed B. To prevent the said weights from acting when not de-

sired, I arrange a spring-clip E, to project inwardly beneath the weights when the latter have reached their upper limit. Thus the weights are held against descending. The 5 horizontal arm of the spring E may project through the case A and have hinged to its outer end a link E', which link may be set into the horizontal arm with its inner end resting against the case A when the spring is 10 drawn outwardly. Thus the springs may be set out of engagement with the weights when it is desired to raise the bed.

Each weight C may be divided into parts 15 c' c², the latter being free to follow the friction-roller C² to its lower limit, while c' descends only part way, being held by a suitable stop. Such a stop is shown at c⁴, which is engaged by a projection c⁵ on the part c' of the weight. In operation, when the bed is 20 nearly or quite closed, only the part c² of the weight rests on the friction-roller; but when the bed descends the part c² ascends and lifts the part c', thus transferring the total weight of the counter-balance to the head of the bed.

25 When the bed B is lowered rapidly, a shock results, unless provision is made for its prevention. When the part c² of the weight meets the part c' of the weight, and when the bed is raised the part c' of the weight leaves the 30 part c² of the weight abruptly, so as to interfere with the steady movement of the bed. To remedy this defect, I insert a spring c⁶ between the parts c' and c². Said spring may be secured to either of said parts and be of 35 any suitable dimensions and strength, and may be fastened upon the end of the part to which it is applied, or may be set into the said part. The action of this spring is obviously to gradually combine and separate 40 the weight of the two parts c' and c². Thus when the bed B is lowered the roller C² will raise the part c² until the spring c⁶ comes into contact with the part to which it is not attached. Said spring then yields, so that the weight of 45 the stationary part c' acts gradually upon the part c². When the bed B is again raised, the part c⁶ does not strike abruptly upon the stop c⁴; but when said part c' meets said stop a considerable portion of the weight of said 50 part c' is still sustained by the spring c⁶, but gradually diminishes until the spring is released entirely from the part c', when the part c² acts alone.

55 At the front and back of the space between the wells D are arranged doors F, so that access is afforded to said space from the front and rear of the bed. From the top wall of said space depends clothes-hooks G.

Two boards B⁴ extend lengthwise along 60 the bottom of the bed and are secured edge-wise to said bottom, and the space between them is filled with a panel. Said bottom is thereby greatly strengthened.

While feet of various forms may be used 65 to support the outer end of the bed when open, I prefer to use the form shown in the drawings.

A board H is laid crosswise over the boards B⁴ near the foot of the bed and hinged thereto in such manner as to allow it to be turned up 70 with its edge directed toward the boards B⁴. Each end of the board H projects a little beyond the adjacent board B⁴, so that a foot H' may be secured to said end between said board H and the bed B. When thus arranged, the legs are set perpendicularly to the bottom of the bed by the turning of the board H upon its hinges. By turning said board back again the legs are folded down beside the boards B⁴. 80

A button I may be suitably secured below the board H, to be turned to hold said board in the perpendicular position.

I claim as my invention—

1. The combination, with the case A, having 85 channels A², in which rest metal bearings A³, of a bed B, having bolts and one or more corner-irons which serve to connect and strengthen the sides and bottom of the folding section B, said bolts binding said corner-irons to the bed and projecting outside of said bed sufficiently to extend into said channel, the heads thereof resting behind said metal bearings, substantially as described.

2. The combination, with the case A, having 90 in its corners the upright ways for weights, a separate weight located in the ways in each such corner, and a wardrobe-space between such weights, of a bed hinged near its head to said case below the weights and supporting said weights through interposed friction-rollers, substantially as described.

3. The combination, with the case A and bed B, hinged near its head within the lower portion of said case and provided at its head 105 with the rollers C², of wells D, located in the corners of said case, and having ways C' and weights C divided into parts, each part having 110 tongues c³, fitting into said grooves C', and a stop being provided for limiting the downward movement of the upper part, said weights being so arranged that the lower one will be engaged by a roller C², mounted upon the head of the bed, and said lower part lifted by said roller against the weight next above, 115 substantially as shown and described.

4. The combination, with the case A and bed B, hinged by its head to said case, of 120 suitably-guided weights arranged within said case and divided into parts to be lifted in succession by the head of the bed, and a spring interposed between said parts, substantially as shown, and for the purpose described.

5. The combination, with the case A and 125 bed B, hinged by its head within the lower portion of the case A, of weights C, arranged to slide in suitable ways within said case and above said head, and divided into parts to be engaged successively by the head of the 130 bed, and having a spring inserted between said parts, one end of such spring being secured to one of said parts, substantially as shown and described.

6. The combination, with the case A and bed B, hinged by its head within the lower portion of said case, of weights C, consisting of upright boxes having lateral tongues to slide in suitable ways in said case and divided into parts, said parts being filled with sand or gravel or similar loose material, and having a spring ^{c6} interposed between said parts and being engaged successively by the head of the bed, substantially as and for the ¹⁰ purposes set forth.
- In testimony whereof I affix my signature in presence of two witnesses.

ANTON LINEE.
